UNITED STATES PATENT OFFICE

CARL DOERR, OF NAUMBURG-ON-THE-SAALE, GERMANY

MULTIPART ARTICULATED REENFORCED-CONCRETE SLEEPER

Application filed October 2, 1929, Serial No. 396,714, and in Germany May 30, 1927.

By the wheel loads acting simultaneous upon both ends of the reenforced concrete sleepers these latter are subjected to bending stresses in their middle portion in so in- 5 favorable a manner that they break at this portion after a short time. In order to overcome this drawback the reenforced concrete sleepers have already been divided into two equal parts and these latter have been yield- 10 ingly jointed to one another in the middle portion of the sleeper by means of bolts.

The improved reenforced concrete sleeper forming the subject-matter of this invention is also twopart and the bolt or pivot connecting these parts with one another is ar- 15 ranged vertically in a socket in which it has some play.

The invention is illustrated diagrammatically and by way of example on the accompanying drawing on which Figure 1 is a side-view of a multipart or twopart reenforced concrete sleeper designed according to this invention; Figure 2 is a plan thereof, and Figure 3 a vertical section through the connect- 25 ing bolt or pivot and the cooperating socket, this figure being drawn to an enlarged scale.

The sleeper halves *a* and *b* overlap one another as at *a*¹ and *b*¹. An upwardly extending bolt or pivot *d* which is tapered at its free end is firmly affixed in the projection *b*¹ of the sleeper half *b*, and engages with some play a socket *c* inserted into the projection *a*¹ of the sleeper half *a*. These members *c* and *d* are shown in Figs. 1 and 2 only in dotted lines, but are shown separately in full lines and on a larger scale in Fig. 3. The frontal faces at the ends of the projections *a*¹ and *b*¹ are not actually vertical, but are a 30 little inclined, and the adjoining horizontal faces are a little convex, as shown in Figs. 1 and 2. Owing to this configuration of the projections and to the plays between the members *c* and *d*, a certain slight angular position 35 of the sleeper halves with respect to one another is rendered possible.

I claim:

1. A multipart articulated reenforced concrete sleeper, comprising two sleeper halves 40 overlapping one another at their adjacent

ends with projections forming parts of said halves, a vertical pivot provided in one of said projections and extending into the other projection, and a socket provided in this other projection and receiving in it said pivot. 55

2. A multipart articulated reenforced concrete sleeper, comprising two sleeper halves having each a projection directed towards the other half, the two projections overlapping one another; a vertical socket in one of said 60 projections, and a bolt in the other projection, this bolt extending into said socket and having some play therein.

3. A multipart articulated reenforced concrete sleeper, comprising two sleeper halves 65 having each a projection directed towards the other half, the two projections overlapping one another; a vertical socket in one of said 70 projections, and a bolt in the other projection, this bolt extending into said socket and tapering at its free end, substantially as set forth.

In testimony whereof I affix my signature.

CARL DOERR.
